UNITED STATES PATENT OFFICE

110,361

DESIGN FOR A PRICE AND TRANSACTION REGISTER DIAL PLATE FOR DISPENSING PUMPS

Edwin C. Mayer, New York, N. Y., assignor to
Neptune Meter Company, Long Island City,
N. Y., a corporation of New Jersey

Application April 2, 1937, Serial No. 68,532

Term of patent 7 years

To all whom it may concern:

Be it known that I, Edwin C. Mayer, being a citizen of the United States, and a resident of the city of New York in the State of New York, have invented a new, original, and ornamental Design for a Price and Transaction Register Dial Plate for Dispensing Pumps, of which the following is a specification, reference being had to the accompanying drawing, forming a part thereof, in which the figure is a perspective view of a price and transaction register dial plate for dispensing pumps showing my new design.

The dominant feature of my design consists in the general outline of the dial plate for the register upon the face of which are design elements comprising a triangle, base upward, and an intersecting horizontal bar, the apex of the triangle overlapping a circular figure.

I claim:

The ornamental design for a price and transaction register dial plate for dispensing pumps substantially as shown and described.

EDWIN C. MAYER.
